320. Inventor:

Charles H. Nichols,

by Geo. St. Maxwell, M.M.

UNITED STATES PATENT OFFICE.

CHARLES H. NICHOLS, OF HAVERHILL, MASSACHUSETTS, ASSIGNOR, BY MESNE ASSIGNMENTS, TO AUTOMATIC ACCOUNTING COMPANY, OF BOSTON, MASSACHUSETTS, A CORPORATION OF MASSACHUSETTS.

APPARATUS FOR COST SYSTEM.

1,105,994.

Specification of Letters Patent.

Patented Aug. 4, 1914.

Application filed August 20, 1908. Serial No. 449,447.

To all whom it may concern:

Be it known that I, CHARLES H. NICHOLS, a citizen of the United States, and resident of Haverhill, in the county of Essex and State of Massachusetts, have invented an Apparatus for Cost System, of which the following description, in connection with the accompanying drawings, is a specification, like letters on the drawings representing like parts.

In large manufacturing establishments, where each article made goes through a number of hands, the detail of whose labor it is desired to determine, and especially where a variety of different styles or the like of particular articles are made, it becomes not only vitally essential but quite difficult to keep the details clearly accounted, as for instance the labor cost accounts. Various systems have been devised, including the coupon card system, and my present invention aims to provide means for rendering such systems more accurate and preventing cheating or other fraud or mistakes.

Stated in general terms, my invention consists in providing, in connection with usual or preferred item slips or blanks, a set of ineradicable and unchangeable marks or means, whereby the particular item is rendered conspicuous which applies to the particular matter, and preferably whereby only that particular item remains properly legible, and preferably I provide a templet or equivalent master plate, whereby any number of said item cards may be mechanically prepared without danger of mistake.

In the more complete embodiment of my invention, I provide gross-account cards in unlimited quantity, to be kept in stock for general use whenever wanted, said cards containing designations, preferably numerical, of all the different items which enter into the business in hand, as, for instance, the cost (or whatever result it is the purpose of the user to determine), or said gross-account cards may be limited to such portion of said items as may be desired or required for some department, branch, or purpose, said items being arranged in groups or classes, each relating to a kindred phase or subject. When therefore, for example, any particular lot

of goods is to be made, the requisite number of these gross-account cards is taken, and all those designations which are not to apply to said particular lot are punched out, or otherwise obliterated, as the case may be, thereby leaving legible solely those designations which apply to said particular lot, or in some other way the latter are made ineradicably distinctive and conspicuous. In this way the gross-account cards are transformed into specific designation cards or specification cards. If said lot is very small these cards are treated individually by hand, but if the lot is large, a templet is first prepared and then the gross-account cards may, if desired, all be treated together. These templets are carefully preserved, and form an accurate means of preparing at a moment's notice the data or specification card for that particular order or style or kind of article whenever wanted without the necessity of investigating the details thereof or otherwise wasting any time whatever, as is required under the methods heretofore in use. And they serve at all times as infallible means of determining what was actually sent out to the employees originally. In a further embodiment of my invention, I employ the templet as a means of printing or otherwise marking the specification cards at the start.

The further details of my invention will appear in connection with the following description, taken with reference to the accompanying drawings, in which I have shown several embodiments of the invention.

In the drawings, Figure 1 is a plan view of a gross-account coupon card or tag; Fig. 2 is a similar view of a templet for use therewith; Fig. 3 is a similar view showing one of the gross-account cards or tags converted into a specification card or tag; Fig. 4 is a fragmentary plan view of a modified gross-account card or tag; Fig. 5 is a fragmentary plan view of a templet for use therewith; Fig. 6 is a fragmentary plan view of the gross-account card shown in Fig. 4 converted into a specification card; Fig. 7 is a fragmentary plan view of another modified gross-account card; Fig. 8 is a fragmentary plan view of a modified form of templet;

Fig. 9 is a fragmentary plan view of a specification card formed by a modified method; Fig. 10 is a plan view of a gross-account card filled out as a general order card for a shoe factory; Fig. 11 is a fragmentary plan view of a card to go with one section of the gross-account card shown in Fig. 10; Fig. 12 is a fragmentary plan view of another card to go with another section 10 of the gross-account card of Fig. 13; Fig. 13 is a fragmentary plan view of another card to go with still another section of the gross-account card shown in Fig. 10. Figs. 14 and 15 show in plan and section the general 15 character of order card shown in Fig. 10, with my system applied thereto, Fig. 16 showing the templet therefor; Fig. 17 is a similar plan view showing a further detail of my invention whereby a time element is 20 combined with the other features above. Fig. 18 is a fragmentary plan view of a card or tag containing letters of designation instead of figures; and Figs. 19, 20, and 21 show in plan a further modification of my 25 invention, Fig. 19 being a bottom plan view of a gross-account card in the form of a type stamp, Fig. 20 the templet to be used therewith, and Fig. 21 the resulting specification card or tag.

30 In carrying out my invention, it will be understood that although I speak of cards or tags, I do not intend to be limited by this term to specific cards technically so called, but intend to include thereby any sheet-like 35 device, stack, pad, and book-form, capable of receiving compiled figures, data or other memoranda or designations, whether the same be a sheet, thick or thin, tag, board, plate, or stack of such, or the like.

40 My invention will be more readily apprehended by describing it with reference to some particular trade, and accordingly I take as the best means of presenting my invention, its use in connection with shoe manufacture, and will first explain it in connection 45 with piece-work.

A series of cards or tags are provided as 1, for instance, preferably marked or otherwise designated in coupon form, so that each 50 workman can tear or cut off the successive coupons 2, these in this case representing labor coupons, which represent the part of the work on a given shoe which any individual workman is called upon to do, and on 55 these cards are listed the different items, representing the processes which the shoe must be put through in the course of its manufacture, and the different prices for the different varieties thereof. In Fig. 4 I have 60 shown these items as marked on the slip in plain reading form at 3 and 4, but some other method may be adopted, preferably a numerical system. For example the shoe manufacturer may tabulate all the work to 65 be done in making shoes in his factory as

follows, which represents the price list of work for all the steps of shoe manufacture grouped in the sequence of making, finishing and packing:

70

Operation.	No.	Kind.	Price per dozen pairs.
Packing	7402		.02
Lacing	7300		.01
Dressing	7223	Kid	.03
	7240	Calf	.02
Treeing	7210	Kid	.15
	7212	Calf	.10
	7214	Patent leather	.12
Stamping	7204	Plain	.01
	7206	With gilt	.03
Wheeling	6200	Foreparts only	.03
	6201	All around	.05
Brushing	6149	Foreparts only	.02
	6150	Whole bottom	.04
Painting	6141		.09
Cutting	6139	Regular	.05
	6140	Fancy	.08
Naumkeaging	6138		.10
Buffing	6135		.18
Burnishing	5132	Regular	.03
	5133	Military	.04
Scouring	5131		.04
Edge setting	5129	double	.12
	5130	English welt	.16
Trimming	5127	double sole	.12
	5128	English welt	.16
Breasting	5126		.02
Shaving	5124	Regular	.03
	5125	Military	.04
Slugging	5121	Half	.02
	5122	Whole	.03
Heeling	5120		.03
Leveling	5119		.06
Fair stitching	5114	double sole	.05
	5115	English welt	.08
	5116	Heel to heel	.12
McKay sewing	5110	Light sole	.06
	5111	Heavy sole	.08
Tacking on	4109		.06
Lasting	4106	Tip toe	.12
	4107	Plain toe	.10
Pulling over	4101	Plain leather tip	.22
	4102	Plain leather plain toe	.20
	4103	Patent leather tip toe	.26
	4104	Patent leather plain toe	.30

100

105

I am attempting herein only to go into the matter sufficiently to make my invention understood. He would similarly tabulate all details of the various other departments of his factory. Having made out a price list itemized as above, so that a designating number represents each different possible step in the shoe manufacture which any individual workman may be called upon to 110 perform for any and all kinds of shoes which a given manufacturer produces, these numbers, thus arbitrarily given, are invariably used thereafter to designate that particular operation and no other. Thereupon these numbers are printed, stamped, or otherwise placed on the cards 1 as indicated at 5, Fig. 1, in check compartments herein shown as corresponding to the coupons 2, so that each workman can check off his work, either 115 by writing his name on the coupon or a number which has been given him, or any other designation by which he checks or identifies with himself the work and price represented by that particular compartment or coupon, or he may place them in an envelop or otherwise segregate them. Each coupon 2 preferably originally contains the numbers for designating all the different prices for the 120 different varieties of any one operation or 125

130

step in the manufacture. I have indicated this preferred arrangement in Fig. 1. In Fig. 7 I have indicated a different arrangement in which the numbers follow consecutively on successive coupons, the main objection to this arrangement being that in some kinds of business it would necessitate an unduly long card or tag. These cards or tags, for instance as shown in Fig. 1, may be printed in immense quantities and kept on hand indefinitely, and constitute the gross-account cards inasmuch as they provide for all the possible requirements of general shoe manufacture, and hence they may be supplied generally on the market in the approved form adopted for the manufacture, for instance.

When a shoe manufacturer wishes to start through the factory any given style or particular shoe, he very carefully picks out all the parts and features which go to make up that particular shoe, and makes a card, or, as I have herein designated it, a templet 6, preferably of hard material, such as leather-board, cardboard or metal, which contains designations 7 so arranged that when compared with the designations 5 of the card 1 they will render conspicuous those individual designations 5 which represent the said parts and features or operations which the various workmen are expected to perform on the shoe. This templet 6 thus constitutes virtually a specification in cipher for the particular shoe or other specific article of manufacture which it is formed to identify, the designations thereon remaining illegible to any one inspecting the same and only coöperating to form a legible specification when brought into combination with the like formed cards containing the multiple sets of selective data. These indications 7 may be almost endless in variety, and they may be so arranged as to render the desired designations 5 conspicuous in a variety of ways, as for instance by punching out a portion of the particular designation 5 of any given coupon indicating the work which it is intended that the workman shall perform, or by punching out all except that particular designation, the latter means being herein shown as the preferred construction. The templet is then applied to a card 1, or the card 1 is treated in accordance with said templet, with the result that the gross-account card is transformed into a specification card as indicated at 8, Fig. 3, where it will be seen that the bottom coupon 2 has the first three designations punched out, thereby leaving the fourth designation "4104" to guide the workman. The card or tag 8 is completed by receiving a designation 9 on each coupon to indicate the number of pairs of shoes which the workman is to make in accordance with that tag or ticket, and a designation

10 to indicate the style or stock number or monogram, trademark, or in fact anything else, and 11 to indicate the lot or case (which is to be stamped, if desired, on the lining of the shoe). These marks may be omitted if preferred.

I prefer to carry out my invention as described above, as thereby the cards may be kept in stock, never requiring change for fluctuating prices, etc. My invention, however, is not limited in this respect, but the prices as well as the operations may be printed out plainly as indicated at 4, Fig. 4. Also, I prefer to employ a punch mark as indicated at 7 which does not entirely obliterate the marks which are punched out or not to be followed, but I do not intend to limit my invention thereto, as larger individual forms 12 of punch may be employed as indicated in Figs. 5 and 6, or elongated or any other shape 13 as indicated in Fig. 8. Instead of actually punching out the paper, the templet may be used as a stencil and the designations 5 may be smeared out as indicated at 14. In other words, the templet is merely a guide or standard-designating card or master card, with reference to which all the cards or tags 8 for that particular kind of shoe are marked. This is the case, irrespective of whether the templet contains holes or any other guiding means.

It will be understood that I am taking the work in a shoe factory merely as a convenient means of making my invention clearly understood, but that, as hereinafter mentioned, I intend my invention for use generally in connection with practically all kinds of businesses. Continuing, however, with my present illustration, I have shown in Fig. 10 the gross-account card which is required, according to my system, for a second department of the factory, viz. the ordering of parts for the shoes which are to be made in accordance with the labor cards 110 8, this consisting of a form of order card or tag which, as before, constitutes the gross-account card or gross-item slip, to be made into a specification card at the proper head office as before, by selecting and designating by reference to a templet or standard those specific items required so that the different kinds and styles of shoes will get started right and in such quantities and varieties as required. For this purpose 115 the order card or tag 15 may, and preferably does, consist of a plurality of parts, four thereof being herein shown, designated as 16, 17, 18, and 19, preferably separated by perforated lines 20, so that, at the proper time, they may be torn apart, to go with the various portions of the shoe which they concern. Accompanying these respective parts will be the work-price cards or tags already described made of course to go with the 120

- particular portion of the shoe as indicated for instance at 21, 22, 23, Figs. 11-13, which will be made out in detail the same as previously explained, as for instance as shown 5 in Fig. 3, each card or tag 21-23 being restricted in its items and other designations to apply solely to those items selected in the corresponding portion of the order sheet or card 15, *i. e.* for instance, the "tops" tag 22 10 being restricted to such matters as apply to the items of portion 17 "tops." As the large order card 15^a would be unduly weakened and cut away if all but the required designations of a given order were cut out, 15 and also as there is no necessity for such extreme caution in this connection, inasmuch as no advantage could accrue to a workman from varying the order, I prefer simply to designate ineradicably those items which go 20 to make up the specific order selected from the general order sheet or card 15^a. This may be accomplished in a variety of ways, but preferably as shown in Fig. 14,—and in this figure I have shown a different arrangement 25 merely so as to indicate still more clearly that I do not intend to limit my invention to any particular arrangement.
- In Fig. 14 I have indicated at 24 the "vamps" portion of a set of general order 30 items. The items are tabulated in any desired arrangement on cards or other sheet-like material, preferably thin, and it may be very thin, like tissue paper. A templet 25 is then provided as already described, preferably of the variety shown in Fig. 8, in which slits are employed, having narrow elongated slits 26 see Fig. 16 cut therein to correspond in position to the items which are to be used in the particular order being sent through 35 the factory, and thereupon the necessary number of thin sheets 24 are cut to correspond to this prepared templet, with the result that each designated item is underscored as indicated at 27, *i. e.* it has a narrow 40 slit cut directly under the item. This may be considered in some factories sufficient, but I prefer to employ the thin paper mentioned and then, having applied the templet marks or cuts to it, paste it on a colored backing 28 45 so that thereby all the items are heavily and conspicuously underscored as by a brush or pen. For instance in Fig. 14 the specification card indicates that a grade A. vamp is to be used, having the top band stamped with 50 the company's own stamp, the top is to be mat goat, the sock lining stamped the same as the top band, to be made of drilling, the vamp lining is to be heavy, and the company's own top band used.
- 55 My invention also includes means for determining whether the returns made by an employee at the end of the day or of the week, for instance, are for work done by him that day or week, or whether he has 60 kept over part of his returns from a previous

extra-easy day or week, and to this end I similarly characterize by some conspicuous distinguishing mark, color, or other designation all the coupons or return slips sent out for the work of a given day, week, or other 70 predetermined period, as for instance I mark two lines 29 vertically of all the cards, as shown in Fig. 3. These two vertical lines 29 are illustrated for example only and if such a distinguishing characteristic were employed it might be desirable to use one line 75 for Monday's work, two lines for Tuesday's, three for Wednesday's, and so on, but any suitable mark, color, or other designation 80 may be utilized, so that the management or the office force can tell at a glance that a particular card is returned within its proper time period.

A further feature is indicated in Fig. 17, where I have shown columns 30, 31 of time 85 spaces, the column 30 indicating the time when a given piece of work is taken by a workman and 31 the time when it is finished, the workman himself stamping the respective items by means of a usual time stamp 90 which is accessible to all. For instance the middle line shows that the workman received thirteen pairs of the given style, etc. of shoes to "tack on" at 1.15 p. m. June 10, and finished at about 1.33 p. m. A workman is 95 naturally ambitious to earn as much as possible, and accordingly he (or any other proper party) may be depended upon to stamp the time promptly, and hence this provision enables the management to keep 100 the foreman to strict account. If the foremen do not distribute the work promptly to the workmen, that fact will show itself in the time stamp reports contained in the time 105 columns 30, 31.

A further feature whereby the management is enabled to keep strict account of the various departments as such, consists in introducing a space or coupon for the foreman or superintendent of a given department to 110 return when the work passes on from his department, as for instance in Figs. 1 and 3 I have shown a coupon 32 for the finishing department, Fig. 3 showing that the specification card when originally made out called 115 for a total cost item in the finishing department indicated by the numeral 149. Accordingly at the end of the day, week, or other predetermined period, the book-keeping department can ascertain immediately from 120 the total of the coupons 32, these in this case representing production coupons, turned in by the finishing department, the total expense which that department should have cost the factory during that period, and by 125 comparing this total with the actual expense of that department, the management can readily determine whether the department is being properly or improperly handled. Heretofore the determining of this result 130

has been an exceedingly complicated, laborious and expensive undertaking in most shoe factories.

It will be understood that similar coupons 5 may be provided throughout the labor specification cards for each department or each special division of the factory which it is desired to keep separate account of, as for instance the stitching room, bottoming room, 10 treeing room, etc. or the making department, finishing department, packing department, or the like.

In Fig. 21 I have indicated a coupon 320 for keeping track of the findings item 15 which, for the given order of that particular card is allowed an expense item "2" (punched out between the "1" and "3"). In this Fig. 21 I have shown a card 33 which bears only those items which go to 20 make up the given specification or specific order of that card or tag, this being sufficient for some small factories and having certain advantages of its own. For this purpose I provide a stamp, which may be a 25 rubber stamp, or any other type stamp 34. This stamp contains the complete list of items designated in accordance with the system preferred, whether by letters, numerals, or both, or any other means, the same as for 30 instance the gross-account cards of Fig. 1. A templet 35 is then prepared in the same manner exactly as the templet previously described, excepting that it is provided with openings 36 corresponding in shape and size 35 approximately to the item designations of the stamp 34. Having prepared this templet, it is placed on a card and the stamp, properly inked, is then alined properly thereon and pressed downward, thereby 40 printing the card 33 as shown in Fig. 21, inasmuch as only those designations are permitted to print through on to the card 33 which aline with the openings 36 of the templet.

45 Whenever any particular operation, ordinarily performed, is omitted, so that a given coupon would be blank, it is desirable that this coupon shall be canceled, and accordingly I employ some suitable canceling 50 means, as for instance the stamp; Fig. 19, is provided with a column of "Void" designations, so that in use the templet, Fig. 20, would be provided with an opening 36 to permit the proper coupon to be marked 55 "Void," whenever not to receive any other mark.

In Fig. 18 I have shown letters 37 for indicating the desired items instead of figures, and it will be understood that I do not 60 intend to limit myself in any way in this respect. For instance in the labor schedule, under "Pulling over," plain leather may be indicated by "1," patent leather by "2," with a tip by "A," and with a plain toe by 65 "B," so that "1A" would indicate a plain

leather tip toe, "1B" a plain leather plain toe, "2A" a patent leather tip toe, etc., or the labor price may be indicated by letters, as for insance the four price items under "Pulling over" may be designated by "A," 70 "B," "C," "D" respectively. So in the order schedule, the different items may be represented by successive numbers or they may be arranged in groups, and each group may have its individual successive numbers, 75 as for instance:

Part.	Kind.	No. or No.	
Vamps.....	Kid.....	1	1
Quarters.....	Box calf.....	2	2
Tops.....	Velours.....	3	3
	Gunmetal.....	4	4
	Patent calf.....	5	5
	Patent coit.....	6	6
	Mat calf.....	7	7
	Mat goat.....	8	8
Weight.....	Heavy.....	1	9
	Medium.....	2	10
	Light.....	3	11
Foxing.....	Circular.....	1	12
	Straight.....	2	13
	Fancy.....	3	14

90 The manner of using my apparatus is as follows: The stack of cards, or the several different stacks of cards, being provided, and provided with data to cover all situations, the manufacturer carefully makes out 95 a templet or master card for each department, *i. e.* for each variety of specification card required to cover the particular matter in hand. For example, he makes out a templet for the order card 15, and then takes 100 the requisite number of order cards required for that particular order of shoes, and marks them all quickly and with certainty to correspond to the templet. Also he carefully makes out a templet 6 for the labor specification cards, marked preferably as shown in Figs. 11-13 for each different kind, style, or variety of shoe. The templet is usually made by taking one of the gross-account cards as a guide by which the templet is 110 punched or with reference to which it is punched or otherwise formed. He then takes the requisite number of cards or tags 1 to go with the order of shoes of any given kind or variety, and marks thereon, preferably adjacent the right hand edge, the quantity, style, and case numbers 9, 10, 11, and also preferably the date or time period designation 29, and then marks these cards or tags in accordance with the templet 6 corresponding to that kind or variety of shoe. 115 This produces the tags 8 which thus marked go through the factory with the shoes, usually attached to the rack on which the shoes are placed, or to the shoe that carries the 120 order tag. As each workman performs his allotted task toward the making of the shoe, he tears or cuts off from the tag the coupon 125 which indicates his work (it being understood that said coupons are preferably 130

arranged from the bottom up in the order of the successive operations on the shoe. The next lot of shoes that comes along to the workman is provided with the appropriate tag 8, which may or may not be the same as the preceding one, but in any event corresponds to the templet for that particular kind or variety of shoe. So on throughout the day. At the end of 5 the day the workman has cut off a large number of coupons 2 from probably a large variety of tags, which he marks with his name or other understood designation, and all these coupons are then collected 10 from all the workmen doing piece-work and taken to the accounting, or cost, or book-keeping department, or paymaster's department. The book-keeping is exceedingly 15 simple, as all that is necessary is to add up the amounts represented by the indicated 20 price marks on all the coupons of any one workman, and the total indicates what he has earned that day.

In the preferred embodiment of my invention, in which all the price marks excepting the indicated ones are actually punched out, it is not only impossible for the book-keeping department to make any error, but it is impossible for the workmen 25 to deceive or work any fraud by changing the same, as the remaining space or spaces for price designations on that particular coupon have been obliterated. For instance 30 the bottom coupon, Fig. 3, in connection with the tabulated key before given for 35 illustration shows the bookkeeper that the workman who turned in that coupon is entitled to 30¢ per dozen for having pulled over the patent leather plain toe shoes on 40 each of the thirteen pairs of shoes in lot #987,581, and the next coupon shows that 45 that particular workman is entitled to 10¢ per dozen for having lasted the plain toe shoes on each of said thirteen pairs of shoes.

If everything is indicated by plain name and figure, as in Fig. 6, the brushing coupon indicates that the workman is entitled to four cents for brushing the whole bottom of 50 each of said thirteen pairs of shoes, and the next coupon shows that the particular workman who turned in that coupon is entitled to five cents for wheeling all around the shoes on each of said pairs of shoes, 55 while the next coupon indicates that the particular workman who turned it in is entitled to one cent for performing the plain stamping operation on each of said pairs of shoes.

60 In using the more complete embodiment of my invention, the time columns are also used preferably as a part of the card containing specification details, as just explained, which the workman fills out as already 65 explained, thereby tending to speed

the work of the factory by enabling the management to keep better track of the foremen, and also the department coupons 70 320 are preferably used, thereby aiding the management in keeping track of the difficult matters as already explained in connection with these coupons. If the factory is small, instead of keeping a large supply of cards 1, 15, or the like, it is necessary merely 75 to provide a stamp or stamps which are used in connection with the templet cards or plates 35 and blank or partially blank cards 38.

The main feature of my invention resides in providing, in connection with a series of cards, tags or similar parts, a master templet, card, or other means capable of being referred to and used, whereby are prepared sets of specification cards which invariably indicate all the specific data for the given matter in hand, and in its more specific embodiment the main feature of my invention resides in punching out or otherwise permanently defacing or obliterating and destroying certain of the items, preferably 90 those which are not to be used, but whether the ones used are punched out or the ones not used are punched out, the result in either case is to render conspicuous one place designation of cost (or whatever the item may designate) so that not only the workman but all concerned may know absolutely which one it is and that it is correct when it reaches the accountant. By arranging these designations in a predetermined 100 order for the entire work of the factory so that each item has its predetermined position as well as its predetermined character (whether numeral, word or otherwise), and by treating all the cards or tags for a given article in accordance with a standard card or templet, the possibility of cheating is eliminated, the work of the accountant simplified, and the original preparation of the cards or tags facilitated, besides introducing rigid system into the factory. If for any reason a manufacturer prefers to retain all the coupons or check compartments 105 2 integrally together, each workman simply marks his name, number or other designation on his portion 2 of the main card or tag 8 but does not sever it from the card or tag, relying upon the line marks 15 to separate or individualize the different portions 2. I intend to include by the above 110 terms not only cost features but shop orders, requisitions, and all matters which can conveniently be listed on tags, tickets, detail cards, or the like.

I do not intend to limit my invention to any particular manufacture, and it will also be understood that my invention is capable of a wide range of embodiments, those herein shown being illustrative of the wide scope of the invention. For example, my 130

invention is readily applicable to clothing and underwear factories, machine shops, metal-working plants, tin and sheet metal ware factories, carriage and automobile factories, watch factories, furniture, chair, wood-working plants, shirt and collar factories, type-writer factories, and the manufacture of electrical, rubber, leather, glass goods, etc. and in short wherever the business requires the selection of specific items from a general classification of items, including extensive billing, etc.

The templet is merely a master card or means which controls the marking or forming of the specification cards, so that all the specification cards which are marked with reference to a given templet will be absolutely alike, and in carrying out my invention in its more advanced embodiment I cut, stamp, or otherwise make out the specification card by an automatic machine; and accordingly it will be understood that by the word "templet" I mean to include any such master means of reference medium, whether in the shape of a card or forming a part of a machine, which, in connection with punching or marking appliances, results in having all the specification cards of a given group or subject formed alike.

Having described my invention, what I claim as new and desire to secure by Letters Patent is:

1. In an apparatus of the kind described, a card containing a set of symbols to distinguish itemized data covering optional selective details comprising a specification of an article of manufacture, and a templet or master card, having means spaced and arranged similarly to certain of the items on said symbol containing card, said means serving as a guide to be coöperative in rendering certain of the distinguishing symbols on said data card distinctive through elimination of the remaining symbols, and converting it into a legible specification for a particular article of manufacture.

2. In an apparatus of the kind described, a card containing a set of symbols to distinguish itemized data covering optional selective details, comprising specification items for a series of similar articles of manufacture, and a master card, or templet, having means spaced and arranged similarly to certain of the symbols on said symbol card, and constituting a cipher specification of a particular article of manufacture, said means being coöperative in rendering certain of the symbols on said symbol card distinctive to convert it into a definite, legible specification.

3. In an apparatus of the kind described, a card containing a set of symbols in tabulated arrangement to distinguish itemized data covering optional selective details, comprising a specification of an article of manufacture, and a templet or master card, containing a series of designating means spaced and arranged similarly to certain of the items on said symbol card and adapted to coöperate with said symbol card to designate particular scattered symbols on said symbol card to convert the same into a definite specification.

4. In an apparatus of the kind described, a card containing symbols in tabulated arrangement to distinguish itemized data covering optional selective details, comprising specification items for a series of similar articles of manufacture, and a templet or master card, containing perforations spaced and arranged similarly to certain of the symbols on said symbol card, constituting a cipher specification and adapted to coöperate with said symbol card and to identify certain of the symbols thereon and convert the same into a definite legible specification of a particular article of manufacture.

5. In an apparatus of the kind described, a card containing multiple sets of optional selective symbols to indicate itemized data, comprising specification details for a series of similar articles of manufacture, and means constituting a cipher specification for a particular one of such articles of manufacture, arranged to coöperate by a punch or the like with said symbols as located on said symbol card to render distinctive certain of the details thereon, and convert the same into a legible specification for said article of manufacture.

6. In an apparatus of the kind described, a card containing a set of symbols to indicate itemized data covering a given general subject in a form outlined into a series of check compartments, each containing one or more of said symbols, and having an adjacent blank space, said card having a series of punch marks to render unmistakably conspicuous a given set of selected symbols of a specific article or subject included with the general subject, and a templet adapted to coöperate with a plurality of such cards to locate said punch marks.

In testimony whereof, I have signed my name to this specification, in the presence of two subscribing witnesses.

CHARLES H. NICHOLS.
